UNITED STATES PATENT OFFICE

2,442,667

SUCTION CLEANER WITH PNEUMATIC FILTER CLEANER

Donald G. Smellie, Canton, Ohio, assignor to The Hoover Company, North Canton, Ohio, a corporation of Ohio

Application April 26, 1943, Serial No. 484,516

5 Claims. (Cl. 183—37)

1

The present invention relates to suction cleaners in general and more particularly to a suction cleaner incorporating automatic filter-cleaning mechanism. More specifically, the invention comprises a suction cleaner of the type which has one or more dirt separators which function to remove the collected foreign material from the carrying air stream, in combination with automatically actuated means which remove the dirt from the dirt collector in order to prevent the building up of a back pressure in the cleaner.

It is an object of the present invention to provide a new and improved suction cleaner. It is another object of the invention to provide a new and improved suction cleaner incorporating filter-cleaning means. A further object of the invention is to provide a suction cleaner in which a dirt separator is automatically cleaned by new and novel means. Still another object of the invention is to provide a suction cleaner in which air-filtering means are provided with cleaning mechanism which is actuated by an improved means. A further object of the invention is to provide a suction cleaner of the type incorporating an initial dirt separator, suction-creating means, a final dirt separator, in combination with a cleaning nozzle for the final separator, which is connected to the initial separator and which is actuated by a new and novel drive mechanism. These and other more specific objects will appear upon reading the following specification and claims and upon considering in connection therewith the attached drawings to which they relate.

Referring now to the drawings in which a preferred embodiment of the invention is disclosed and in which the same reference character refers to the same parts in the various views;

Figure 1 is a vertical section through a suction cleaner constructed in accordance with the present invention;

Figure 2 is an enlarged partial section through the nozzle-actuating mechanism constructed in accordance with the present invention; and

Figure 3 is a transverse horizontal section upon the line 3—3 of Figure 2 showing the filter-cleaning-nozzle-actuating mechanism.

In the operation of the usual common and well known type of suction cleaners the dirt-laden air stream is filtered by a dust bag which functions to retain the collected foreign material and to permit the carrying air to escape into the ambient atmosphere. After a certain amount of foreign material has collected within the bag, however, the resistance to the passage of air, known as

back pressure, increases to a point where the flow of air through the machine is materially reduced and the cleaner efficiency is adversely affected. In such machines the bag must then be moved and emptied in order that the machine be returned to its initial operating efficiency.

Suction cleaners have been designed incorporating mechanical dirt separators making use of the centrifugal principle to separate the collected foreign material from the carrying air stream. Such machines, in order to be of greatest efficiency, should be provided with a final filter as taught in the patent to Bible 2,247,472. In the Bible construction, and in similar cleaners, means must be provided to clean the final filter to prevent its back pressure from increasing unduly as in the case of the dust bag in the ordinary type of machine. In the suction cleaner constructed in accordance with the present invention this final filter is cleaned automatically by a filter-cleaning nozzle which is interiorly connected to the initial separator and is automatically actuated by a novel mechanism in the operation of the machine itself. This novel actuating mechanism can also be used in a machine having but a single filter which must be cleaned.

Referring again to the drawings, a suction cleaner is disclosed which is seen to comprise a large cylindrical casing 1 provided with a centrally apertured and flanged bottom plate 2, and with a top plate 3. Casing 1 seats upon a supporting base 4 which houses a dirt pan or collector 5 sealed to the bottom plate 2.

An inner central cylindrical casing 7 is divided by a transverse wall 8 into a lower whirl chamber 9 and into an upper fan chamber 11. The latter chamber is itself divided into first and second stages by a stationary multi-vaned deflector 12 formed with a central aperture 13 which functions as the inlet port between the two stages.

A downwardly extending inlet 14 extends into the vertical whirl chamber 9 below the mid-portion thereof and forms the inlet connection between the whirl chamber and the fan chamber.

A vertical rod 16 is carried by spiders 17 within inlet passageway 14 and detachably supports a transversely extending plate 18 near its lower end and immediately above the dirt pan 5 and also supports a strainer 19 immediately below the lower spider 17. Plate 18 is of a diameter slightly less than that of the whirl chamber 9 and accordingly there is provided a peripheral circular opening around the plate 18. Whirl chamber 9 is itself formed with an inlet chamber, indicated 55 at 21, to which connects an inlet port 22 adapted

to receive and seat a dusting tool hose 23 which is provided at its outer end with the usual cleaning nozzle 24.

A driving motor 26 is mounted upon the top plate 27 of casing 7 and the motor shaft 31 extends downwardly into the fan chamber 11 where it carries suction-creating fans 28 and 29 within the first and second stages of fan chamber 11, respectively.

Fan chamber 11 is provided with exhaust ports 33 which interiorly connect it with a surrounding filter chamber 34 defined by a cylindrical wall 36 of suitable air-filtering material which is secured at its lower edge to a flanged bottom plate 37 seating on the exterior of the cylindrical casing 7 in sealed relationship, and at its top by a depending flange 38 secured to the top wall 3 of casing 1. The enclosing space within the main casing 1 and around the filter chamber 34 is called the discharge chamber and is indicated by the reference character 39. The latter chamber is connected to the atmosphere through the discharge port 41 in the casing 1, which port incidentally is adapted to seat dusting tools in the manner of inlet port 22 should it be desired to use the machine as a blower rather than as a suction tool.

The cleaner motor 26 is provided with electric current over suitable incoming power leads 42 which pass through the casing 1 and through a sealing bushing 43 in plate 37 on their way to the motor 26 which, as is seen in Figure 1, is positioned in the final filter chamber 34. As in the usual cleaner, a manually operable switch 44 is provided by which the operator can control the flow of current and so the operation of the machine.

The machine which has been heretofore described comprises an operative suction cleaner and has but one shortcoming, to-wit, no means have been provided to clean the final filter 36 which functions to remove from the air passing through the cleaner any foreign material which has escaped from the initial separator or whirl chamber 9. The means and structure which accomplishes this filter-cleaning action will now be described.

A filter-cleaning nozzle 46 is positioned adjacent and in contact with the inside of the final filter 36 being of a length substantially equal to the height of that element. Nozzle 46 is provided with an inlet opening through which cleaning air is adapted to be drawn and is rotatably supported by a conduit seat 47 which encircles the upwardly extending portion of the motor shaft 31, being supported thereon by a sealed bearing 48. Seat 47 is also supported by a bearing 49 carried by the upwardly facing mouth of a second conduit seat 51 which is fixedly mounted on the top of the motor casing and extends therefrom downwardly along the side of that casing and also the fan chamber 11 to connect interiorly to the whirl chamber 9 at its inlet chamber 21. The relationship is such that the reduced pressure or suction present within the whirl chamber at the inlet 21 will also be present within the filter-cleaning nozzle 46.

As the filter-cleaning nozzle 46 is relatively narrow at its mouth it is necessary to move the nozzle over the filter in order to clean the entire surface of the latter. This is accomplished by means of a novel drive mechanism located just below the top wall 3 of the cleaner, and which is itself driven by the motor shaft 31. It is not feasible to drive the filter-cleaning nozzle 46 at

the speed of rotation of the motor shaft 31 for obvious reasons and, accordingly it is necessary to provide means which will reduce the speed of nozzle travel. In the present invention this is accomplished by providing at the upper end of the motor shaft 31 a planetary gear reduction mechanism. A sun pinion 56 is carried directly by the motor shaft adjacent an internally threaded gear 57 carried by a shouldered cup element 58 secured to the casing wall 3. Cup member 58 carries a bearing 61 at its center concentrically of motor shaft 31 which bearing rotatably supports a frame 62 comprising a cup-shaped portion enclosing the motor shaft 31 in spaced relationship and a plate surface extending perpendicular to the motor shaft 31 and immediately below gears 56 and 57. Frame 62 is also centered and rotatably positioned relative to the motor shaft 31 by a second bearing 63 which is positioned within its cup-shaped portion. Frame 62 carries a planet gear or pinion 64 which meshes with both the sun pinion 56 and the internal gear 57 and, in the rotation of the motor shaft 31, revolves at reduced speed about the motor shaft.

Frame 62 carries below the bearing 61 a grooved cam 66 which rotates with the frame as it rotates with the revolution of the planet pinion 64. The entire planetary gear construction and cam is enclosed within a rotatable protecting housing 67. This housing also serves as a base for a spring 68 which exerts a force upon the top of conduit seat 47 to maintain it in proper seating relationship with its supporting bearing 49.

The rotation of the cam 66 is translated into a slow step-by-step movement of the nozzle 46 by means of an actuating lever 71 which is pivoted at 72 upon a supporting base 73 carried by the upper end of the nozzle 46. Actuating lever 71 carries a cam follower 74 which rides the rotating cam 66 being held in contact therewith by the action of a coil spring 76 located at the pivot pin 72 and which exerts a force between an abutment 77 on that support and the adjacent arm 71.

Actuating lever 71 is U-shaped in section, as is illustrated in Figures 2 and 3, and at its nozzle end beyond its pivotal axis 72 carries, by means of a second pivot pin 78, a trailing ratchet foot 79 which contacts at its roughened or serrated base a fixed tracked surface formed by the inner surface of filter-supporting flange 38. A second coil spring 81 is carried by the lever 71 at the pivot 78 of the ratchet foot 79 and exerts a force between an abutment 82 on lever 71 and the trailing foot to force the latter into contact with the stationary surface or track 38.

As the outer end of the actuating lever 71 is carried by the support 73 fixed to the nozzle 46 it is clear that any movement of the lever 71 at its pivot point will be accompanied by movement of the rotatably mounted nozzle 46. The pivotal movement of the inner end of actuating lever 71 under intermittent forces received from the eccentric cam 66 effects the advancement of the outer end of the lever arm 71 and accordingly of the nozzle 46 in the following manner.

The cam follower 74, rigid with the actuating lever 71, is movable between the full line and the dotted line positions illustrated in Figure 3. With the follower moved outwardly from the motor shaft, the full line position illustrated in Figure 3, the lever 71 extends substantially radially with respect to the motor shaft and the encircling flange 38. Upon the movement of the follower 74 radially inwardly towards the motor shaft to the dotted line position illustrated in Figure 3,

the outer end of the lever 71 with the foot 79 will advance clockwise, as viewed in Figure 3. As the cam continues its rotation and the follower 74 is advanced outwardly again, the outer end of the lever 71 carrying the ratchet foot 79 can conceivably do one of two things. Either it can return to its former position of radial alignment without movement of the nozzle or, using the contact of the trailing ratchet foot 79 with the encircling flange or track 38 as a support, the lever 71 at its pivotal axis 72 can be advanced clockwise. Actually this last is what happens for the frictional resistance of the contact of the ratchet foot 79 with flange 38 is such that when the lever arm 71 attempts to move in a counter-clockwise direction about its pivotal axis 72 the force exerted by the coil spring 81 upon the trailing ratchet foot 79 is sufficient to hold the latter in contact with the flange 38 and the result of the actuating force upon the lever 71 is merely to advance in clockwise direction the lever at its pivot point 72. As the lever at its pivot point 72 is rigidly connected to the supporting base 13 which in turn is rigid with the nozzle 46, it is clear that this slight advance of the lever arm in a clockwise direction has been accompanied by a corresponding advance of the filter-cleaning nozzle.

The operation of the machine is believed to be clear from the foregoing, but in summarizing it can be said that in normal operation cleaning air with any collected foreign material is drawn through the cleaning nozzle 24, the dusting tool hose 23 and enters the initial dirt separator or whirl chamber 9 via the inlet port 22. The action of the rotating air stream in the vertical whirl chamber is such that centrifugal force throws the collected foreign material radially outward and it drops downwardly into the dirt container or pan 5. The cleaned air passes upwardly through the inlet 14 into the fan chamber 11 under the action of the suction-creating fans 28 and 29. The air is exhausted from the fan chamber into the final filter chamber 34 and passes outwardly through the final filter 36 into the exhaust or discharge chamber 39 and from there into the surrounding atmosphere via the exhaust port 41. The rotation of the motor in driving the fan effects the actuation of the filter-cleaning nozzle 46 as described above and as that nozzle moves around the interior surface of the filter 36 it removes therefrom the collected foreign material which has escaped from the initial separator 9. During the nozzle movement a reversed air stream is drawn from the discharge chamber 39, through the filter 36, and into the nozzle 46 under the action of the suction in the conduit 51 which connects directly to the whirl chamber 9 at its inlet chamber 21. As a result of this cooperation it is never necessary for the user to clean the final filter 36 as all foreign material is collected within the dirt pan 5 which can be cleaned when necessary by withdrawing it transversely from its base 4, or if preferred, the main casing 1 can be removed from the base 4 to permit of the upward displacement of the container 5.

I claim:

1. In a suction cleaner, suction-creating means, a motor to drive said means, and an air-permeable filter to filter continuously the dirt-laden air passing through the cleaner under the action of said suction-creating means; a filter-cleaning nozzle mounted for movement relative to and in contact with the dirt-collecting surface of said

- filter to maintain the back pressure on said suction-creating means substantially constant, air-conducting means connecting said nozzle to said suction-creating means to draw a cleaning air stream therethrough, and means connecting said filter-cleaning nozzle to said motor to actuate said nozzle relative to said filter comprising means reciprocated by said motor and movable with said nozzle, and a pivoted wedge element carried by said reciprocated means in contact with a surface fixed relative to said filter and adapted to exert an intermittent moving force on said reciprocated means and said nozzle in the reciprocation of the former.
- 5 2. In a suction cleaner, suction-creating means, a motor to drive said means, and an air-permeable filter to remove continuously foreign material from air passing through said cleaner under the action of said suction-creating means; a filter-cleaning nozzle mounted for movement relative to and in contact with the dirt-collecting surface of said filter to maintain the back pressure on said suction-creating means substantially constant, air-conducting means 10 connecting said nozzle to said suction-creating means to draw a filter-cleaning air stream therethrough, and a planetary gear reduction mechanism driven by said motor, a slow speed eccentric cam driven by said mechanism, a pivoted lever mounted on said nozzle for reciprocating movement by said cam, and a wedging foot pivoted on said lever for advancement on a rigid surface fixed relative to said filter upon the pivotal movement of said lever.
- 15 3. In a suction cleaner, suction-creating means, a motor to drive said means, and an air-permeable cylindrical filter continuously to remove foreign material from air passing through said cleaner under the action of said suction-creating means; a filter-cleaning nozzle mounted for slow speed movement relative to and over the dirt-collecting surface of said filter to maintain the back pressure on said suction-creating means substantially constant, air-conducting means 20 connecting said nozzle to said suction-creating means to draw a filter-cleaning air stream therethrough, a planetary gear reduction mechanism driven by the shaft of said motor, an eccentric cam driven at reduced speed by said mechanism and rotatable about the axis of said motor, a pivoted lever mounted for movement with said filter-cleaning nozzle and connected to said cam, a circular track fixed relative to said filter, and a ratchet foot pivotally mounted on said lever for frictional engagement with said track adapted to exert a lever-and-nozzle-moving force upon the pivotal movement of said lever under the actuation of said cam.
- 25 4. In a suction cleaner, an initial dirt separator, suction-creating means to draw a dirt-laden air stream into said initial separator and to draw substantially clean air therefrom, a final dirt separator of the type in which the back pressure increases with accumulation of dirt to receive air from said suction-creating means and remove therefrom all foreign material escaping from said initial separator, a motor to drive said suction-creating means; movable dirt-collecting-and-removing means to remove the foreign material 30 from said final dirt separator including an air conduit directly connecting said means to said initial dirt separator, actuating means for said dirt-collecting-and-removing means comprising a planetary gear reduction mechanism driven by said motor, a cam driven at relatively slow
- 35 5. In a suction cleaner, suction-creating means, a motor to drive said means, and an air-permeable cylindrical filter continuously to remove foreign material from air passing through said cleaner under the action of said suction-creating means; a filter-cleaning nozzle mounted for slow speed movement relative to and over the dirt-collecting surface of said filter to maintain the back pressure on said suction-creating means substantially constant, air-conducting means 40 connecting said nozzle to said suction-creating means to draw a filter-cleaning air stream therethrough, a planetary gear reduction mechanism driven by the shaft of said motor, an eccentric cam driven at reduced speed by said mechanism and rotatable about the axis of said motor, a pivoted lever mounted for movement with said filter-cleaning nozzle and connected to said cam, a circular track fixed relative to said filter, and a ratchet foot pivotally mounted on said lever for frictional engagement with said track adapted to exert a lever-and-nozzle-moving force upon the pivotal movement of said lever under the actuation of said cam.
- 45 6. In a suction cleaner, an initial dirt separator, suction-creating means to draw a dirt-laden air stream into said initial separator and to draw substantially clean air therefrom, a final dirt separator of the type in which the back pressure increases with accumulation of dirt to receive air from said suction-creating means and remove therefrom all foreign material escaping from said initial separator, a motor to drive said suction-creating means; movable dirt-collecting-and-removing means to remove the foreign material 50 from said final dirt separator including an air conduit directly connecting said means to said initial dirt separator, actuating means for said dirt-collecting-and-removing means comprising a planetary gear reduction mechanism driven by said motor, a cam driven at relatively slow
- 55 7. In a suction cleaner, suction-creating means, a motor to drive said means, and an air-permeable cylindrical filter continuously to remove foreign material from air passing through said cleaner under the action of said suction-creating means; a filter-cleaning nozzle mounted for slow speed movement relative to and over the dirt-collecting surface of said filter to maintain the back pressure on said suction-creating means substantially constant, air-conducting means 55 connecting said nozzle to said suction-creating means to draw a filter-cleaning air stream therethrough, a planetary gear reduction mechanism driven by the shaft of said motor, an eccentric cam driven at reduced speed by said mechanism and rotatable about the axis of said motor, a pivoted lever mounted for movement with said filter-cleaning nozzle and connected to said cam, a circular track fixed relative to said filter, and a ratchet foot pivotally mounted on said lever for frictional engagement with said track adapted to exert a lever-and-nozzle-moving force upon the pivotal movement of said lever under the actuation of said cam.
- 60 8. In a suction cleaner, an initial dirt separator, suction-creating means to draw a dirt-laden air stream into said initial separator and to draw substantially clean air therefrom, a final dirt separator of the type in which the back pressure increases with accumulation of dirt to receive air from said suction-creating means and remove therefrom all foreign material escaping from said initial separator, a motor to drive said suction-creating means; movable dirt-collecting-and-removing means to remove the foreign material 65 from said final dirt separator including an air conduit directly connecting said means to said initial dirt separator, actuating means for said dirt-collecting-and-removing means comprising a planetary gear reduction mechanism driven by said motor, a cam driven at relatively slow
- 65 9. In a suction cleaner, suction-creating means, a motor to drive said means, and an air-permeable cylindrical filter continuously to remove foreign material from air passing through said cleaner under the action of said suction-creating means; a filter-cleaning nozzle mounted for slow speed movement relative to and over the dirt-collecting surface of said filter to maintain the back pressure on said suction-creating means substantially constant, air-conducting means 70 connecting said nozzle to said suction-creating means to draw a filter-cleaning air stream therethrough, a planetary gear reduction mechanism driven by the shaft of said motor, an eccentric cam driven at reduced speed by said mechanism and rotatable about the axis of said motor, a pivoted lever mounted for movement with said filter-cleaning nozzle and connected to said cam, a circular track fixed relative to said filter, and a ratchet foot pivotally mounted on said lever for frictional engagement with said track adapted to exert a lever-and-nozzle-moving force upon the pivotal movement of said lever under the actuation of said cam.
- 75 10. In a suction cleaner, suction-creating means, a motor to drive said means, and an air-permeable cylindrical filter continuously to remove foreign material from air passing through said cleaner under the action of said suction-creating means; a filter-cleaning nozzle mounted for slow speed movement relative to and over the dirt-collecting surface of said filter to maintain the back pressure on said suction-creating means substantially constant, air-conducting means connecting said nozzle to said suction-creating means to draw a filter-cleaning air stream therethrough, and means connecting said filter-cleaning nozzle to said motor to actuate said nozzle relative to said filter comprising means reciprocated by said motor and movable with said nozzle, and a pivoted wedge element carried by said reciprocated means in contact with a surface fixed relative to said filter and adapted to exert an intermittent moving force on said reciprocated means and said nozzle in the reciprocation of the former.

speed by said mechanism, a lever pivoted on said dirt-collecting-and-removing means and movable therewith, said lever including a cam follower to effect the pivotal movement of said lever upon the movement of said cam, a track adjacent said final dirt separator, and means cooperating with said lever and said track to advance said dirt-collecting-and-removing means relative to said final dirt separator upon the pivotal movement of said lever.

5. In a suction cleaner, an initial dirt separator, suction-creating means to draw a dirt-laden air stream into said initial separator and to draw substantially clean air therefrom, a cylindrical final dirt separator including a filter to receive air from said suction-creating means and remove therefrom all foreign material escaping from said initial separator, and a motor to drive said suction-creating means; a filter-cleaning nozzle mounted for rotation about the axis of said motor and in contact with and over said filter; an air conduit connecting said filter-cleaning nozzle to said initial dirt separator, actuating means for said dirt-collecting-and-removing means comprising a planetary gear reduction mechanism mounted on the shaft of said motor, a cam rotatable about said motor shaft and driven at relatively slow speed by said mechanism, a pivoted lever mounted on said nozzle for movement there-

with relative to said final dirt separator and including a cam follower to effect the pivotal movement of said lever upon the rotation of said cam, a track adjacent said final dirt separator, a pivoted ratchet foot carried by said lever in contact with said track and adapted to exert a nozzle-moving force on said lever upon the pivotal movement of said lever in one direction.

DONALD G. SMELLIE.
